UNITED STATES PATENT OFFICE

JOHN T. JANETTE, OF CHICAGO, ILLINOIS

BODY-TREATMENT MACHINE

Application filed November 19, 1928. Serial No. 320,330.

This invention relates to machines of the vibratory type which may be used either with or without belts or other appliances for giving treatment to the body.

5 The objects of this invention are to provide an improved machine of this type which will be simple in construction and will have the operating parts enclosed or arranged so that there will be little danger of injury to 10 a person using the same; to provide a massaging machine having motor driven appliances which are actuated at a reduced speed from the motor whereby the applicator will have proper timing to produce the best results; to provide a massaging machine having oscillating or vibrating levers or arms for actuating the massaging members or for 15 direct action on the person to be treated; to provide a massaging machine having handles 20 or hooks which are driven to produce a more or less elliptical or rotary movement; and to provide such other improvements and details of construction as will be hereinafter described.

25 In the accompanying drawings illustrating a preferred commercial form of my invention, Figure 1 is a perspective view;

Figure 2 is an enlarged sectional view taken on the line 2—2 of Figure 3;

30 Figure 3 is a front view of the motor and operating members with parts broken away or shown in section; and

Figure 4 is a sectional view taken on the line 4—4 of Figure 3.

35 In the machine as shown in these drawings, I provide a base or platform 5 upon which the person to be treated stands. This platform has a post or column 6 which is secured thereto and extends upwardly a convenient distance to support the operating mechanism. A frame or block 7 is secured to the upper end of the column by means of bolts 8 and carries the motor 9 which is fastened thereto by screws 10. The body of the

40 motor may be secured to the post 6 or bear against the same, as shown in Figure 2. The motor shaft 11 has pulleys 12 secured to either end thereof which are engaged by belts 13 which in turn drive pulleys 14 on 45 a countershaft 15 which has its bearings 16

in the frame or headblock 7. Eccentrics 17 are keyed or otherwise secured to the shaft 15 and are fastened to the pulleys 14 by means of screws 18, the arrangement being such that the pulleys, eccentrics and shaft are 55 driven in unison. The eccentrics 17 are engaged by eccentric straps or bearings 19 on cranks or arms 20. The rings or bearings 19 are held in position on the eccentrics by means of disks or plates 21 which are held by screws 60 22 in the ends of the shaft 15 and also by screws 18.

The arms or levers 20 are provided with slots 23 for engagement with sleeves or cross-heads 24 on pins 25, which pins are fastened 65 in arms or projections 26 extending out from the main frame 7. The outer ends of the arms 20 have handles or hooks 27 which may be grasped by the hands of the person to be treated or to which may be attached a belt or strap as shown at 28 or any other suitable applicators for engagement with the body. The position of the sleeve or bearing 24, as shown in the drawings, is such that it gives 70 a substantially elliptical movement to the handles 27 with the main axis of the ellipse in a horizontal plane. The position of the bearings, however, may be changed so that the hooks or handles will have either a circular movement, or if desired, an elliptical movement with the major axis in a vertical plane 75 as will be readily understood.

The frame 7 has integrally formed disks 29 at either end thereof which are engaged by protective guards or shields 30 which cover 80 the pulleys and eccentrics and which are also provided with channel-shaped extensions 31 which extend over the lugs or brackets 26 and tend to prevent any accidental contact of the person with the pivotal bearings of 85 the arms.

The eccentrics are preferably positioned on the shaft in opposite relation to each other so that the hooks or handles will move in opposite directions whereby the strap or belt 90 28 may be drawn back and forth over any part of the person to which it may be applied.

When the device is to be used, the motor is started which drives the countershaft through the double drive which insures 100

steady and even movement and at the same time reduces the strains on the apparatus. The rotary movement of the countershaft is changed to a crank movement for the pivoted arms by means of the eccentrics or other suitable connections and such movement causes the arms to be reciprocated or moved longitudinally as well as swung or moved up and down at either end thereof. The position of the fulcrums or pivots 25 may be arranged to give any desired components to the movement of the handles, which in the arrangement shown will have a substantially elliptical movement. This movement will not only transmit a longitudinal or back and forth movement to the strap or belt 28 but will also move the ends thereof up and down which increases the effectiveness of the treatment. Furthermore, the belt 28 may be placed in a vertical or suspended position as for treating the feet and even in this position will have a substantial vibratory or massaging action imparted thereto. The speed of the motor is reduced through the reduction drives so that the vibratory arms will be given a relatively slow movement or movement such as is best adapted for physical treatment in order to produce the most satisfactory results.

30 This also permits the person to be treated to grasp the handles 27 for receiving vibratory treatment for the arms; consequently the upper portion of the body. In place of the closed strap or belt 28, a single strap may be applied to either one of the hooks and brought into engagement with any desired part of the body as by being wound around the same in order to give a variation in treatment.

40 It will be noted that the operating portions of the machine might be secured to a wall or other support instead of being arranged on a pedestal and other changes may suggest themselves as coming within the scope of this invention which is set forth in the following claims, in which I claim:

45 1. In a massage machine, the combination of a main frame, means for supporting the frame, a motor secured to the frame, pulleys mounted on each end of the motor shaft, a countershaft mounted in said frame, pulleys on said countershaft, belts engaging with the pulleys on the motor shaft and countershaft, levers having slots therein, pins on the main frame engaging with said slots, and means actuated by the pulleys on the countershaft for giving rotary movement to the inner ends of said levers, the outer ends of the levers having hooks or the like.

50 60 2. A movement cure or treatment machine comprising a base for supporting a person to be treated, a column secured to the base, a main body secured to the column, a motor suspended from the main body, pulleys on each end of the motor shaft, a countershaft

mounted in the body, pulleys on the countershaft, belts engaging with the pulleys on the motor shaft and countershaft for driving the countershaft, eccentrics secured to the pulleys on the countershaft and also secured to the countershaft, crank arms having bearings engaging with the eccentrics and having slots spaced from said bearings, bearing members secured to the frame and engaging with said slots, hooks on the outer ends of the crank arms, an applicator adapted to engage with the hooks, said main body having outwardly projecting guard members adjacent to the pulleys, and outer guard members covering the pulleys and main portions of the crank arms.
